[57] CLAIM

The ornamental design for a rattle, as shown and described.

DESCRIPTION

FIG. 1 is a side elevational view of a rattle showing my new design,

FIG. 2 is a side elevational view thereof, as seen from the right of FIG. 1;

FIG. 3 is a top plan view thereof, and

FIG. 4 is a bottom plan view thereof.

The unshown aspects of the design opposite what is shown in FIGS. 1 and 2 are substantially mirror images to thereof.

FIG. 1.

FIG. 2.

FIG. 3.

FIG. 4.
